UNITED STATES PATENT OFFICE.

WALTER E. AMBERG, OF CHICAGO, ILLINOIS.

LATERAL-MOTION BEARING FOR RAILWAY-TRUCKS.

1,144,520.

Specification of Letters Patent. Patented June 29, 1915.

Application filed July 16, 1913. Serial No. 779,296.

To all whom it may concern:

Be it known that I, WALTER E. AMBERG, a citizen of the United States, residing at Chicago, in the county of Cook and State of Illinois, have invented certain new and useful Improvements in Lateral-Motion Bearings for Railway-Trucks; and I do hereby declare the following to be a full, clear, and exact description of the invention, such as will enable others skilled in the art to which it appertains to make and use the same.

My invention has for its object to provide an extremely simple and highly efficient lateral motion bearing for railway trucks, and to such ends, generally stated, the invention consists of the novel devices and combinations of devices hereinafter described and defined in the claims.

More specifically stated, this invention relates particularly to a lateral motion device employing upper and lower bearing plates of one form or another, and interposed elliptical or flattened rockers or rollers. Stated still in another way, the rockers are provided in their sides with reentrant portions which coöperate with the stops 11 for the purpose stated; and the plate engaging surfaces of the said rockers are in such curved lines that they give the rockers increasing cross sections measured through the axes of said rockers, obliquely to a vertical line drawn through the axes of the rockers when the rockers are in neutral position shown in Fig. 4. The above described curve of the rockers provides an arrangement in which the rockers, under the weight of the load, will be yieldingly centered and automatically returned to centered positions even when used in connection and coöperating with upper and lower bearing plates having flat or approximately flat rocker engaging surfaces.

The invention resides in the novel coöperative arrangement of stops on the bearing plates and channels in the sides of the rollers.

In the accompanying drawings which illustrate the invention, like characters indicate like parts throughout the several views. Referring to the drawings: Figure 1 is a fragmentary view in side elevation, showing a portion of a car truck frame and certain associated devices including one of my improved lateral motion bearings; Fig. 2 is a vertical section taken on the line $x^2 x^2$ on Fig. 1; Fig. 3 is a plan view of the lower bearing plate; and Fig. 4 is an enlarged

view in diagrammatic vertical section, illustrating the action of the improved rocker.

Of the parts of the truck, the numeral 1 indicates the truck side frame, the numeral 2 the truck springs, and the numeral 3 the truck bolster, which latter is mounted for vertical and endwise movements through openings in the side frames. The springs 2 support a lower roller bearing plate 4, which, in this illustrated arrangement, serves also as a spring cap. This roller bearing plate 4 has the usual large notches 5 in its ends which embrace bolster guiding surfaces 6 of the side frames and cause the said bearing plates 4 to partake of the lateral movements of the truck frame while permitting vertical movements thereof. The upper roller bearing plates 7 may be formed as a part of the truck bolster 3, as shown, or it may be separately formed and suitably secured thereto.

Between each coöperating pair of bearing plates 4 and 7, is interposed a pair of elliptical or flattened rollers or rockers 8, which, in their opposite sides, are formed with longitudinal channels 9 that are preferably approximately V-shaped in cross section. The elliptical upper and lower surfaces of the rollers 8 are seated on flat surfaces 10 of the upper and lower bearing plates 4 and 7, and at the extremities of the said bearing surfaces 10, the said bearing plates are formed with outside and intermediate stops 11. Obviously, these elliptical rockers support the bolster 3 with freedom for lateral movements, that is, for endwise movements transversely of the truck. When the rockers are oscillated to extreme positions, the walls of their channels 9 will be engaged with stops 11 of the lower bearing plate, and with stops 12 of the upper bearing plate, as indicated by dotted lines in Fig. 4. Thus, the rollers and stops are caused to limit the endwise movements of the bolster. The engagement between the walls of the roller channels 9, and the coöperating stops 11 and 12, further serves, under each extreme movement of the bolster, to re-align the rockers and to set the same accurately, in respect to the stops, if, in fact, they should creep or work themselves out of such proper alignment.

The upper and lower surfaces of the rockers 8 are described as elliptical, and preferably, they are segments of a true elliptical curve. They may, however, be true cylindrical curves, in which case, the arc of the

curves on which they are formed, should have a diameter considerably greater than the vertical dimensions of the rockers, so as to thereby give an increasing resistance to movements of the bolster from its normal or intermediate position, and so that also, the bolster, under the weight of the load thereon, will be automatically returned to its normal intermediate position and yieldingly held in such position.

The improved lateral motion bearing may, of course, be applied in car trucks or other railway trucks, elsewhere than between the truck side frames or parts mounted thereon, and the truck bolster. In fact, they may be applied at any desirable place between the car truck body and the wheels, where they will operate to permit lateral movements of the said body in respect to the wheels.

What I claim is:

In a lateral motion bearing for cars, the combination with upper and lower bearing

plates having approximately flat rocker engaging surfaces and stops at the extremities thereof, of rockers interposed between the said flat bearing surfaces of said upper and lower bearing plates and having their sides formed on reentrant lines that interrupt their curved plate-engaging surfaces, the said reentrant surfaces being directly engageable with said stops to align said rockers and re-set the same properly, in respect to said stops, the said curved plate-engaging surfaces of said rockers being on line which increase the diameters of the cross sections thereof, when measured through the axes of said rockers obliquely to a normal perpendicular through the axes thereof.

In testimony whereof I affix my signature in presence of two witnesses.

WALTER E. AMBERG.
